UNITED STATES PATENT OFFICE.

GUSTAVE STICKLEY, OF SYRACUSE, NEW YORK.

DESIGN FOR A CHAIR-BODY.

SPECIFICATION forming part of Design No. 35,082, dated September 10, 1901.

Application filed July 22, 1901. Serial No. 69,331. Term of patent 7 years.

all whom it may concern:

Be it known that I, GUSTAVE STICKLEY, a citizen of the United States, residing at Syracuse, in the county of Onondaga, State of New York, have invented and produced a new and original Design for Chair-Bodies, of which the following is a specification, reference being had to the accompanying drawing, in which I show the same in an isometrical view.

As shown in the drawing, the leading or material feature of my design comprises a chair-body as a unitary article, in which A and B are the side frames, united by a front and rear cross-bar *a* and *a'*, extending clear through the uprights, as shown at *b* *b'*. The side frames A and B have angular uprights or legs *c*, intersecting the flat arm-piece *d*, the rear outer corner of which is cut off, as shown at *d'*, and said uprights pass through the said arm-piece, as shown at *e*. *f* and *f'*

are cross-bars connecting the lower ends of the legs *c* and passing through them, as shown at *g*. *m* designates flat bars arranged vertically at substantially equal distances apart between the upper edge of the bars *f* and *f'* and the under face of the arm-piece *d*, the whole body of the chair-frame thus forming a unique and artistic piece of furniture.

Having thus described my invention, what I claim, and desire to secure by Letters Patent, is—

The design for a chair-body substantially as herein described and shown.

In witness whereof I have hereunto set my hand this 9th day of July, 1901.

GUSTAVE STICKLEY.
